Patented July 25, 1922.

UNITED STATES PATENT OFFICE.

LEWIS D. CHRISTIE, OF NICHOLS, CONNECTICUT, ASSIGNOR TO ALBERT OPPENHEIM,
OF NEW YORK, N. Y.

HOSE-SUPPORTER BUTTON AND METHOD OF MAKING SAME.

1,423,599.

Specification of Letters Patent. Patented July 25, 1922.

Application filed June 17, 1921. Serial No. 478,281.

To all whom it may concern:

Be it known that I, LEWIS D. CHRISTIE, a citizen of the United States, residing at Nichols, county of Fairfield, State of Connecticut, have invented an Improvement in Hose-Supporter Buttons and Methods of Making Same, of which the following is a specification.

This invention relates to clasp-studs such as are used in garment supporters, and the like, and to the method of making the same, and has for an object to provide an improved stud consisting of a head, shank and base, which shall be formed mechanically from a blank of wire, and particularly to provide a new and improved method of applying the rubber collet to the metal-stud to complete the same.

With these ends in view I have devised the novel wire-stud and the method of making the same which I will now describe.

Referring to the accompanying drawings forming a part of this specification, Fig. 1 is a view in elevation illustrating the use 25 of my novel stud in a garter. Fig. 2 is a section on line 2—2 of Fig. 1, looking in the direction of the arrows. Fig. 3 is a top plan view of the stud detached. Fig. 4 is a perspective view of the rubber collet which 30 encloses the head and shank. Fig. 5 is an elevation looking from the left of Figs. 3 and 6. Fig. 6 is an elevation looking from the bottom. Fig. 7 is an elevation looking from the right of Figs. 3 and 6. Fig. 8 is 35 a perspective view of the stud detached. Fig. 9 is a perspective view at substantially right angles to Fig. 8. Fig. 10 is a perspective view showing the stud with the head or eye elevated or turned up to receive the collet. Fig. 11 is a perspective view of the 40 stud with collet in place on the shank but with the head or eye still turned up and Fig. 12 is a perspective view of the completed stud with the collet in place and the head 45 or eye bent down into position in the flaring recess in the top of the collet.

Reference numeral 1 denotes the band of a garter which may be of any ordinary material or design, and 2 the ordinary metallic 50 clasping loop, which in use engages the stud as clearly shown. The clasping loop is attached to the band in any ordinary or preferred manner, as by a loop 3 of textile web, and the stud is carried by a longer loop 4

of textile web, which is also attached to the 55 band.

The stud comprises a head or eye 5, a shank 6, and a base 7. The head which in the finished stud lies approximately parallel to the plane of the base, is formed from the 60 portion of a wire blank adjacent one end 8 thereof, said blank being curved to form an approximately circular head of the required size. In forming the stud, however, the head is not made parallel to the base, but 65 extends upwardly at an angle or is elevated above the top of the shank as shown in Fig. 10, and is not bent down to the position parallel to the base as shown in Figs. 2 to 9 until after the rubber collet has been 70 placed on the shank. Just under the head the blank is bent inward and downward at 75 9 to form one strand of the shank, it being noted that the head overhangs the shank. At the lower end of the shank the blank is bent 75 outward at 10, at approximately a right angle and is then curved and recurved at 11 to form one end of the web-slot 12. It is again curved and recurved at 13 to form the other end of web-slot 12 and extends 80 inward to the base of the shank where it is bent upward to form a second strand 14 of the shank. It is then curved and recurved or bent upon itself at 15 immediately under the head 5 and extends downward to form 85 the third strand 16 of the shank. The blank then extends outward at approximately right angles and is curved and recurved at 17 to form one end of the second web-slot 18. The other end of this slot is formed by curving 90 and recurving the blank at 19 and the blank then extends inward to the base of the shank and is bent upward to form the fourth strand 20 of the shank, the end 21 terminating where it will be immediately under the 95 head after said head is bent down to horizontal position. The strand 20 lies closely adjacent the strand 9, and when the head is in the raised position, as shown in Fig. 10, the end 21 is in line with one side of the 100 head 5 and therefore will not interfere with the application of the collet now to be described.

The stud is completed by placing thereon a yielding collet 22 which is molded from 105 rubber. The upper end of the collet is enlarged as at 23, and is provided with a recess 24 which receives the head 5 of the

stud, the recess being preferably large enough to receive the head so that the latter will lie wholly below the upper end of the collet after it is bent downward to its final position. The ordinary method of applying the collet is to force it over the head of the stud while this head is in the position it occupies in the finished stud; that is, substantially parallel with the base. When the 10 collet is put on with the head in that position the lower or smaller body portion thereof must be stretched to at least the external diameter of the head. With my method of applying the collet, however, the 15 head is turned up as shown in Fig. 10 when the collet is applied, and is then turned down with the recess in the top of the collet as shown in Figs. 2 and 12. In slipping the collet over this head while it is turned up 20 the collet is not stretched nearly as much as in the old method as it flattens out in passing over the head. As it is not stretched excessively it fits the shank more snugly. Furthermore, after the head has been turned 25 down it holds the collet in place more firmly than it does when the collet is applied by the usual method. It is of course immaterial whether the collet is threaded onto the stud or the stud is inserted in the collet. 30 The stud is attached to web-loop 4 by passing one end of the loop downward through one of the slots 12 or 18, then across and upward through the other slot, then around backward and under the stud, the 35 ends of the loop being stitched or otherwise secured to the garter band.

Having thus set forth the nature of my invention, what I claim is—

1. The method of making clasp-studs 40 which consists in forming the stud comprising a base, a shank and a substantially circular head from a wire blank with the head upturned at an acute angle to the shank, then slipping a tubular collet over the head 45 and onto the shank, and then bending the head down to hold the collet in place.

2. The method of making clasp-studs 50 which consists in forming the stud comprising a base, a shank and a substantially circular head from a wire blank with the head

upturned at an acute angle to the shank, threading a tubular collet having a flared upper end over the head and onto the shank, and bending the head down into the recess in the flared upper end of the collet. 55

3. The method of making clasp-studs which consists in forming the stud comprising a base, a shank and a head from a metal blank with the head upturned with respect to the shank, then passing a tubular collet over 60 the head onto the shank, and then bending the head into contact with the end of the collet.

4. The method of making clasp-studs which consists in forming from a wire blank 65 the stud comprising a base, a shank and a head with the head upturned with respect to the shank, threading a tubular collet over the head and onto the shank, and bending the head toward the collet to retain it in 70 place on the shank.

5. A clasp-stud formed from a wire blank and comprising an approximately circular head formed at one end of the blank, the blank being then bent downward to form one 75 strand of a shank, the blank being then bent outward and curved and recurved twice to form a web-slot, then bent upward to form a second strand of the shank and bent downward upon itself immediately under the head 80 to form a third strand of the shank, then bent outward and curved and recurved upon itself twice to form a second web-slot and finally bent upward to form the fourth strand of the shank and terminating under 85 the head.

6. A clasp-stud formed from a wire blank with its mid-length bent upon itself to form 90 two strands of a shank, the parts of the blank being then bent outward at substantially a right angle and then bent away from each other and curved and recurved twice to form web-slots, and then bent inward and upward to complete the shank, one of said parts being bent to form an approximately 95 circular head overhanging the shank and the other half terminating under said head.

In testimony whereof I affix my signature.

LEWIS D. CHRISTIE.
